ROLL-FEED APPARATUS FOR A FACSIMILE TRANSCEIVER

Robert E. Kalvitis, Fairport, N.Y., assignor to Xerox
Corporation, Rochester, N.Y., a corporation of New
York

Filed May 9, 1968, Ser. No. 11,860

Term of patent 14 years

Int. Cl. D14—01

U.S. Cl. D26—14

FIG. 1

FIG. 2

FIG. 3

FIG. 4

FIGURE 1 is a left-hand front perspective view of a roll-feed apparatus for a facsimile transceiver, showing my new design.

FIGURE 2 is a top plan view thereof.

FIGURE 3 is a front elevational view thereof.

FIGURE 4 is a side elevational view thereof.

I claim:

The ornamental design for a roll-feed apparatus for a facsimile transceiver, as shown.
